COMPOSITE WRAPPING MATERIAL

Thomas M. Royal, Philadelphia, Pa., assignor, by
mesne assignments, to Ramco, Inc., a corpora-
tion of Delaware

Application May 19, 1934, Serial No. 726,557

7 Claims. (Cl. 229—87)

My invention relates to wrappers for articles of merchandise and more particularly to a type of composite wrapper which includes a transparent area. A composite wrapper of the type to which 5 my present invention is related is disclosed in my prior application for patent, filed July 11, 1931, Serial No. 550,252.

The composite wrapper of this application comprises sections of paper or similar material, 10 more or less opaque in character, flanking the edges of and secured to a transparent section which is preferably a form of cellulose hydrate. While other sheet material of a transparent character may be employed, it is preferred that the 15 transparent section be made of cellulose hydrate of a moisture-proof type; that is to say, a cellulosic product of a highly transparent nature, familiarly known as "cellophane", which has been treated with a surfacing material rendering the 20 same substantially air- and moisture-proof.

Composite wrapping material is in more or less general use and is employed for the wrapping of various commodities as, for example, bread; the wrapper usually displaying some form of advertising matter or the like, or an indication 25 of the contained goods. Various methods have been employed to prepare these composite wrappers as, for example, by associating sections of paper or similar material which are maintained in 30 more or less registering position when run through a machine of suitable character whereby such paper sections may be associated with and permanently connected to an intermediate 35 section of highly transparent material, preferably a form of moisture-proof cellulose hydrate.

When these composite wrappers are intended to be employed as enclosures for food products, one practice has been to provide sections of paper which are waxed. In order that such sections 40 of waxed paper may be in condition to receive and be properly adherent to an intermediate section of transparent material—cellulose hydrate of the moisture-proof type or the like, as the case may be—it has been the practice to omit the wax 45 coating on each surface adjacent one edge of each waxed paper sheet in order that a margin or selvage of plain untreated paper is left to facilitate connection therewith of the moisture-proof or other section of cellulose hydrate, inasmuch as 50 some difficulty has been encountered in attempting to secure the transparent material, whether of cellulose hydrate or other character, to the waxed surface.

The object of my invention is to avoid all of 55 the difficulties heretofore present in the prepara-

tion of composite wrapping material of this general nature which has been and is employed to a very great extent in the packaging of various edible commodities, bread wrapping being a notable instance of its use; and to provide a composite 5 wrapper including completely waxed paper sections secured to and flanking a transparent section, cellulose hydrate of a moisture-proof type, or the like, which will maintain the article enclosed thereby in air-tight condition. 10

And a further feature of my invention is to provide an improved wrapper of a composite character with waxed paper portions imprinted over the entire surface, including the intermediate 15 transparent portion.

These and other features of my invention are more fully described hereinafter, reference being had to the accompanying drawing, more or less diagrammatic in character, in which:

Figure 1 is a perspective view of a section of 20 composite wrapping material of the character to which my invention has been applied.

Fig. 2 is a similar view showing such composite wrapping material imprinted with suitable indicia to indicate the character of the product enclosed 25 thereby.

Fig. 3 is a similar view of the finished wrapper showing the waxed condition of the paper sections.

Fig. 4 is an enlarged sectional view of my im- 30 proved composite wrapper taken on the line IV—IV, Fig. 3, and

Fig. 5 is a fragmentary perspective view on a much larger scale illustrating a detail of my invention. 35

In the manufacture of these composite wrappers for use in the packaging of various articles of food—bread, for instance—the side sections of paper flanking the section of highly transparent material—cellulose hydrate or the like—have 40 been waxed, and these waxed sections have had printed matter displayed thereon. These paper sections may be printed prior to assembly with the highly transparent intermediate section, and as they sometimes contain matter designed for 45 registry, considerable difficulty has resided in the attempts to form satisfactory wrappers from such material. While it may be possible to effect substantially a desired registry of two independent printed paper sections of a composite wrapper, in all likelihood it would be necessary to employ special means coordinating or cooperating with the printed sections to insure this desired registry, with the attendant additional expense. All of this is avoided by the arrangement 50 55

which I have proposed, in which the printing operation is applied to the completed composite wrapping material, such printing extending over the entire surface of the composite wrapper; 5 that is to say, over the side sections as well as over the highly transparent intermediate section, after all of such sections have been associated and permanently secured together.

In the method heretofore employed in the making 10 of composite wrapping material having marginal sections of partially waxed paper, there has always existed an unsealed portion between the intermediate section of cellulose hydrate or other transparent material and the waxed portions 15 of the paper sections, because it has been necessary to leave unwaxed a marginal portion of such paper sections to which the cellulose hydrate or other transparent material is connected, and this has militated against its use to a certain extent.

In the drawing, the composite wrapper is shown as composed of sections of paper which may be of any suitable character, indicated at A, and a section of transparent material which may be 25 cellulose hydrate of a moisture-proof type or the like, indicated at B. The inner marginal edges *a* of the respective paper sections overlap the outer marginal edges *b* of the intermediate section of cellulose hydrate or other transparent material to which edges they are secured by lines of adhesive in the usual manner.

In Fig. 2, the section of composite wrapping material is illustrated as having been overprinted with suitable indicia which may represent the 35 contents or goods enclosed thereby, the name of the dealer, etc., such imprinted indicia being indicated at *x*.

In Fig. 3, I have shown a section of the finished wrapping material in which the marginal sections 40 of paper are illustrated as coated with a waxy body C, common in the manufacture of waxed papers and the like. This waxy body extends over the entire body of the paper sections to the marginal edges thereof which flank the 45 section of transparent material or cellulose hydrate which constitutes a window between the inner marginal edges of the paper sections. On the underside of the wrapping material—that is to say, the portion which shows the marginal edges *b* of the cellulose hydrate or other transparent material as overlying the marginal edges of the paper—the wax coating C is brought over such marginal overlapping edges of the cellulose hydrate or other transparent material so that 55 both surfaces of the entire material of the composite wrapper which flank the actual transparent area are fully coated.

In carrying out my present invention, the paper sections and the section of cellulose hydrate 60 or other transparent material intermediate the same are secured together in any suitable manner. The three sections may be run between suitable rolls, as indicated in my prior application above-referred to, or a plurality of double-width paper sections and a plurality of the intermediate highly transparent sections, cellulose hydrate of a moisture-proof type or the like, may be connected in any manner, more or less common in the art and then the double-width sections 65 of paper may be separated by suitable slitting means after permanent connection of the transparent sections with the marginal edges of such paper sections. The paper sections in this condition of the composite wrapper are plain, unwaxed elements.

The next step is to imprint the composite wrapper with desired indicia, as indicated in Fig. 2. This imprinting may be all over the wrapping material, as indicated in Fig. 2, or only the paper sections may be imprinted.

The next step is to subject the composite web to suitable wax-applying means which will serve to completely wax coat the paper sections up to and including both marginal edges of the same directly adjacent the transparent sections, which 10 may be cellulose hydrate or other suitable material having similar characteristics, which overlie the paper sections. The wax coating is applied on both surfaces of the composite wrapping material, as may be understood, and the wax 15 coating on that side of the composite wrapper where the edges of the cellulose hydrate section overlie the marginal edges of the laterally disposed paper sections extends to such marginal edges of the cellulose hydrate, as clearly indicated 20 in Fig. 5. This insures a wrapper which is moisture-proof throughout the entire width and effects complete sealing between the waxed side sections of paper or the like and the intermediate highly transparent section, and provides an air- 25 tight wrapper for application to any commodity, the waxed portions thereof, as well as the section of cellulose hydrate, being susceptible of heating for complete sealing in the final wrapping of the package.

In the manufacture of my improved composite wrapping material, the printing step may follow directly the connection of the separate webs of paper and transparent material, cellulose hydrate or the like, and as soon as the printed surface 35 is dry, the wax coating may be applied. This wax coating may be applied in any suitable manner that will insure complete coating of the surfaces of the paper sections, together with the overlying marginal edges of the central section of 40 transparent material—cellulose hydrate or the like—but without touching that portion of the latter which actually forms the window between the marginal paper sections.

A distinct advantage of my improved method 45 of making the composite wrapping material resides in the fact that, after the several sections or sheets have been connected, it may be printed from side to side with the assurance that the printing on one of the marginal paper sections, for 50 instance, will be in absolute registry with and exactly match the printing applied to the other marginal section of paper, with or without printed matter upon the transparent section intermediate said paper sections.

I have referred herein to the use of "cellulose hydrate" as the transparent section of my improved composite wrapper, and such term is intended to indicate the material familiarly known as "cellophane", whether plain, moisture-proof, or that type known in the trade as "M. S. T." I do not wish to be limited to the use of "cellophane"—plain, moisture-proof, "M. S. T." type, or otherwise—as the transparent portion of my improved composite wrapping material, however, and I may 65 employ the so-called "crystalline" or "glassine" of commerce; gelatin; celluloid; pyralin, or any other transparent material sufficiently flexible to be employed in the formation of packages or as the wrapping of various forms of packages, boxes, 70 or other container, and the like, when associated with the waxed paper sections making up the composite wrapping material which I have developed.

While my improved composite wrapping mate- 75

rial is available for use as unit wrappers or wrappings for various commodities, or various forms of packages, boxes, and the like, it will be understood that it may be employed in all forms of 5 wrapping machines employed for covering various commodities, or boxes, cartons, or the like, containing the same, or packaging machines in which mechanism for forming a container operates in advance of a filling operation, label-pasting operation, etc., without departing from my invention.

It will also be understood that my improved composite wrapping material—moisture-proof throughout its entire extent—may be employed 10 in the manufacture of various types of enclosures which might include a tubing step in their formation. In tubing such material, the seam of the tube may be joined by heat and/or pressure—means other than pasting—or if pasting is desired 15 the surfaces of the overlapping portions may be scratched or abraded sufficiently to remove so much of the wax coating as to permit the use of an adhesive connection, and such scratching or abrading may be carried out in the manner set 20 forth in my pending application filed December 25 19, 1930, Serial No. 503,594.

It will be understood that modifications may be made in the method of producing my improved composite wrapping material and in the material 30 employed in its manufacture without departing from my invention, all of which is within the scope of the appended claims.

I claim:

1. The herein described method of making 35 composite wrapping material which consists in joining one marginal edge of a plurality of sections of paper to the marginal edges of a section of transparent material disposed intermediate said paper sections; said transparent section defining a window between the paper sections, and wax coating both surfaces of said sections of paper up to the margins of the window defined by said intermediate transparent section.

2. The herein described method of making 45 composite wrapping material with imprinted indicia which consists in joining one marginal edge of a plurality of sections of paper to the marginal edges of a section of transparent material disposed intermediate said paper sections; said transparent section defining a window between the paper sections, imprinting the surface of the several sections making up such composite wrapping material, and wax coating both surfaces of said imprinted sections of paper up to the margins of the window defined by said intermediate transparent section; said wax coating covering the marginal edges of the transparent section overlapping the marginal edges of the paper sections.

60 3. As a new article of manufacture, a com-

posite wrapper comprising marginal sections of paper and a central section of transparent material permanently secured to a marginal edge of each of said paper sections; said section of transparent material defining a window between the 5 paper sections, and a coating of wax covering both surfaces of said paper sections and extending up to the margins of the window defined by said section of transparent material.

4. As a new article of manufacture, a composite wrapper comprising marginal sections of paper and a central section of transparent material having its edges overlying and permanently secured to a marginal edge of each of said paper sections; said section of transparent material defining a window between the paper sections, and a coating of wax covering both surfaces of said paper sections and extending up to the margins of the window defined by said section of transparent material; said wax coating covering the 10 15 overlapping edges of the central section of transparent material.

5. Composite wrapping material comprising a section of paper and a section of coated "cellophane" defining a transparent area; the meeting 25 edges of the paper section and the "cellophane" overlapping and being permanently secured together, and a coating of wax extending continuously over at least one surface of the paper and over the surface of the lapping portion of the 30 "cellophane" substantially to the transparent area and sealing the joint between such overlapping portions.

6. Composite wrapping material comprising 35 oppositely disposed sections of paper and a section of coated "cellophane" disposed between the same and defining a transparent area; the meeting edges of the paper sections and the "cellophane" overlapping and being permanently secured together, with a coated surface of the 40 "cellophane" between the overlapping or meeting edges of the paper, and a coating of wax covering the paper sections and extending along a portion of the coated "cellophane" substantially 45 to the transparent area.

7. Composite wrapping material comprising 50 oppositely disposed sections of paper and a section of coated "cellophane" disposed between the same and defining a transparent area; the meeting edges of the paper sections and the "cellophane" overlapping and being permanently secured together, with a coated surface of the "cellophane" between the overlapping or meeting edges of the paper, and a coating of wax covering the paper sections and extending into the region 55 of the union of the adjacent outer edges of the "cellophane" and the overlapping portion of the paper sections substantially to the transparent area.

THOMAS M. ROYAL. 60
